UNITED STATES PATENT OFFICE.

CHARLES F. KLOSS, OF NEW HAVEN, CONNECTICUT.

SAFE.

Application filed January 29, 1925. Serial No. 5,627.

This invention relates to safes and more especially to that class of safes which are particularly intended for the protection of currency, documents, papers, records and like matter, from destruction by fire.

Such safes usually consist of inner and outer compartments suitably spaced and supported from each other so that a considerable space is left between the walls of these compartments, this space being filled with certain heat resisting or non-conducting material, so that if the outside of the safe is subjected to heat for a greater or less period of time, the papers and like material stored within the safe, will be insulated from such heat and will be preserved intact. Such safes, however, require a relatively thick layer of packing or heat insulating material between the inner and outer walls, and, therefore, the overall dimensions of the safe are relatively large compared to the available space for the reception of the material to be preserved. That is, while the exterior dimensions of the safe may be relatively large, the interior will present a relatively small space for the protection of material. This is becoming an especially great disadvantage at the present time, due to the fact that floor space is often very valuable in large office buildings, and the protection of papers and records of various kinds is becoming more and more necessary. The problem of storing such records is assuming great importance, and a saving of a considerable part of this space between the walls of the two compartments of the safe is of great advantage, especially as regards the width and depth of the safe, which are the two dimensions which define the amount of floor space required, the space at the top and bottom of the safe being of less importance.

It is also well known that a large part of the cost of a safe is the cost of transporting and installing it, due to its large size and weight, and if the size of the safe can be decreased without a corresponding decrease in its capacity, and its weight lessened, the cost of the safe to the consumer will be considerably lessened, due to the saving in transportation and installation charges.

Further, as it is becoming necessary to preserve great quantities of records and documents, the cost of safe protection for such material presents a serious problem, and it is, therefore, of great advantage to produce a safe which will give ample protec-

tion to the material stored therein, but which will be relatively cheap to manufacture.

Moreover, one of the weak points of a safe is usually that part of the door in which the locking mechanism is housed, for while the remainder of the door may be packed with heat insulating material, it is, of course, not possible to so insulate that part of the door which contains the locking mechanism, and as a result, the safe is usually especially vulnerable to heat at this point.

One object of my invention, therefore, is to provide a safe which will give material stored therein ample protection against heat, but which will, at the same time, occupy a relatively small amount of floor space as compared to the storage capacity for material to be protected. That is to say, the space between the inner and outer walls of the safe, particularly at the four sides thereof, will be reduced to a minimum.

Another object of my invention is the provision of a safe of this character, which will be of relatively light weight when transported, so that it may be shipped and installed at a relatively low cost.

A further object of my invention is the provision of a safe of this character, which while possessing sufficient strength to withstand the shocks to which such devices may be subjected, and while capable of giving the contents ample protection against heat, may be manufactured at a relatively small cost.

A still further object of my invention is the provision of a safe, wherein that part of the door in which the locking mechanism is contained, will be given substantially the same heat insulating properties as the rest of the safe.

More specifically, my invention contemplates the provision of a safe comprising inner and outer compartments having spaced walls, the space between said walls being normally occupied by air and the mounting, at the bottom of the safe, of reservoirs containing a vaporizing fluid, such as water, for example, and providing auxiliary reservoirs in the form of tubes located against the exterior side walls of the safe, these tubes also being filled with the vaporizing fluid and in communication with the main reservoirs.

I also contemplate the placing of a receptacle containing such a fluid in the door of the safe and providing communication between this reservoir and that part of the

door which contains the locking mechanism, so that in case of fire, the generated vapor will be carried into the lock compartment and thereby protect the contents of the safe.

5 To these and other ends, the invention consists in the novel features and combination of parts to be hereinafter described and claimed.

In the accompanying drawings:

10 Fig. 1 is a front elevational view of a safe, embodying my invention, with the door in open position;

15 Fig. 2 is an enlarged perspective view of the safe shown in Fig. 1, with some of the parts broken away to expose the interior;

20 Fig. 3 is a sectional view on line 3 of Fig. 1;

Fig. 4 is a transverse sectional view on line 4—4 of Fig. 3;

25 Fig. 5 is a sectional view on line 5 of Fig. 2;

Fig. 6 is a view of a modified form of safe door;

25 Fig. 7 is a sectional view on line 7—7 of Fig. 6; and

Fig. 8 is a detail view on line 8—8 of Fig. 4, showing the valve structure used.

The preferred form of my invention which I have selected to illustrate and describe, comprises a safe 10, provided with a hinged door 11 and suitable supports 12, although it will be understood that the details of the safe may be varied within wide limits within the scope of my invention.

35 The body of the safe comprises inner and outer compartments 13 and 14, as clearly shown in Fig. 4. The inner compartment will preferably comprise a top, bottom, and three sides or walls, the front being left open 40 for the reception of material, such as documents, papers, etc., and as will be obvious, is closed by the door 11.

The outer compartment 14 will consist of a top and three sides, which will be suitably spaced as shown in Fig. 4, from the corresponding walls of the inner compartment. Suitable structure (not shown) may be provided to firmly brace the two compartments from each other so as to make a strong and 50 rigid safe. The bottom 15 of the outer compartment is preferably removable and is connected to the remainder of the structure by such fastening devices as screws, bolts, or the like (not shown), the supports 12 being secured to this bottom member.

For convenience, I have shown the bottom of the safe divided into three compartments, as illustrated in Fig. 3, the compartments being separated by the diverging 60 members 16, 17 and 18 of a grid secured to the safe structure. This grid assists in bracing the walls of the safe and also provides means for securing the bottom 15 to the rest of the structure. The number of compartments 65 may, of course, be varied if desired.

Within these three compartments in the bottom of the safe are placed tanks or reservoirs 19, 20 and 21, which reservoirs will correspond in cross sectional shape to the shape of the compartments. The reservoirs are entirely closed with the exception that suitable plugs or the like 22, may be arranged so that they may be filled with water or some other suitable vaporizing liquid. As shown in Fig. 3, the reservoirs may have a considerable depth so that a relatively large quantity of this liquid may be stored therein. The space provided at this point between the bottom of the inner compartment and the bottom 15 of the safe, may be relatively large as compared to the space arranged between the side walls of the structure, as no additional floor space is occupied by reason of the former dimensions being relatively large, while the same is not true of the space between the side walls.

The space between the side walls of the safe is entirely occupied by air, with the exception that flat relatively shallow tubes 24, 25 and 26 lead upwardly from the reservoirs and are located within this space. These tubes are preferably located adjacent the exterior wall of the safe so that they will be immediately affected by heat without the safe. While I have shown one of the tubes leading from each of the reservoirs and disposed within each of the three side walls of the safe, it will, of course, be understood that the number may be varied as desired.

The tubes communicate with the reservoirs through valves 27, preferably arranged at the lower ends of the tubes, these valves being so arranged, as will be explained hereinafter, that while they are normally closed they will be opened if steam is generated within the lower reservoirs and also will be opened if the safe falls upon its side or turns upside down.

Similar valves 28 are arranged at the upper ends of the tubes and in this way, the tubes will normally be kept closed, so that there will be no evaporation of the water therein or in the reservoirs 19, 20 and 21.

The air spaces at the three sides of the safe, and at the top, will preferably be in free communication with each other, so that any steam or vapor generated in any of the tubes 24, 25 and 26, or in any of the tanks communicating with these tubes, will pass into this air space and entirely surround the contents of the safe with the exception of the front or door and the bottom. The bottom is, of course, protected by the reservoirs themselves and the door is separately protected, as will be explained hereinafter. Suitable openings 30 may be arranged about the door jamb to provide for the escape of the steam emitted from the tubes.

The valves 27 each consists of a chamber

or the like 31, provided with inlet and outlet ports 32 and 33, controlled by a ball valve 34. The port 32 is in communication with its corresponding reservoir by means of a duct 35, while the port 33 communicates with the corresponding vertically extending tube through the opening 36. Small bleed openings or bypasses 37 and 38 lead around the port 33, so as to provide restricted communication between the chamber 31 and the corresponding tube through the port 36 at all times, it being understood that these bypasses are not controlled by the ball valve 34. The action of this valve is as follows: 10 When the safe is in its normal position and is not subjected to heat, the valve 34 remains in the position shown in Fig. 8, wherein the port 32 is closed and the evaporation of the liquid in the reservoirs is prevented. If vapor is generated in the reservoirs, however, the pressure will cause the ball valve to be lifted and vapor will escape around this valve through the port 33 and the opening 36 into the corresponding tube. If, however, the safe falls upon its side or turns upside down, the ball valve will be dislodged by gravity and will cover the port 32, so as to prevent a rapid escape of the liquid in the reservoirs. A slow drainage of this liquid into the tubes will, however, take place through the bypasses 37 and 38, so that the tubes will be supplied with the vaporizing liquid at all times. 20

The valves 28 at the upper end of the tubes, are constructed similarly to the valves 27. In this instance, the duct 35 communicates with the liquid in the tube, and the port 36 opens into the air space between the walls of the safe. The action of the valve is substantially the same as heretofore explained, the valve preventing evaporation from the tubes when the safe is in normal position, but allowing a slow drainage of the liquid from the tubes when the safe is turned from its normal position. 30

As shown in Fig. 2, the door 11 of the safe is provided with a water reservoir 40, which occupies substantially the entire area of the door with the exception of the portion 41 adjacent the free edge in which the locking mechanism is located. A tube 42 leads downwardly into this compartment from the top of the reservoir so that vapor generated within the reservoir will be carried to that part of the door within which the locking mechanism is housed, so as to provide heat insulation at this point. As shown in Fig. 5, the tube 42 is connected with the reservoir 40 by a valve 43, constructed similarly to the valve 27. 40

When, as shown in Fig. 6, the locking mechanism covers substantially the entire area of the door, a reservoir 44 may be placed in front of the lock structure, the reservoir covering the entire area of the

door. This reservoir is in communication with the lock compartment 45, through the valve 46, which is also similar to the valve 27, so that any vapor generated in the reservoir 44 is communicated to this compartment. The escape of the vapor from the door will take place through the openings provided for the lock bolts, although, of course, additional vent openings may be provided, if desired. 50

The operation of my device is as follows: If the safe is subjected to heat at the bottom thereof, the large reservoirs 19, 20 or 21 will be attacked thereby, and as soon as the heat gains sufficient intensity steam or vapor will be generated in these reservoirs, and will pass upwardly through the valves 27 to the auxiliary reservoirs or tubes 24, 25 and 26 and thence into the air space which surrounds the storage compartment of the safe, so as to protect the material stored therein. If, however, extreme heat happens to be directed against one of the sides of the safe, for example, against the back instead of against the bottom, the auxiliary reservoir 25 will be immediately attacked. As this reservoir is comparatively flat and preferably located adjacent the outer wall of the safe, a hot fire, although of relatively short duration will generate vapor within the tube on account of the comparatively small volume of liquid therein, and this vapor will pass outwardly through the valve 28 to protect the contents of the safe. If such a fire is of sufficient duration to entirely vaporize the liquid within the tube 25, the reservoir 20 will be affected by that time and the liquid therein will be vaporized to afford further protection. It will be seen, therefore, that I have provided auxiliary reservoirs in the structure of the tubes which will become active to protect the contents of the safe during a sudden intense application of heat, and main reservoirs upon which these auxiliary reservoirs may draw, provided the fire is of sufficient duration. 90

In addition, the door of the safe is amply protected not only at that part within which packing material is usually located, but also at that part wherein the locking mechanism is arranged, and that I have, therefore, obviated one of the weak points of a safe from the standpoint of fire protection. 100

It will be apparent that the safe herein disclosed will be relatively cheap to manufacture, as no packing material will be required. Moreover, it will be much lighter in weight than most safes in use at the present time, for in installing the safe the various reservoirs are not filled with liquid 110 until the safe is installed. For this purpose, the safe may be turned upon its side, the bottom 15 removed and the reservoirs with the attached tubes may be withdrawn, filled with water and then replaced so that during 120

shipment and handling of the safe, the weight of the liquid within the reservoirs will not have to be contended with. The bottom is then replaced and secured and the safe is turned to upright position.

While I have shown and described a preferred embodiment of my invention, it will be obvious that it is not to be limited to the details shown but is capable of modification and variation within the spirit of the invention and within the scope of the appended claims.

What I claim is:

1. A safe having a body portion, provided with a storage compartment surrounded in part by hollow walls, a reservoir located adjacent the bottom portion of the safe below said compartment and adapted to contain a vaporizing liquid, a tube mounted in the hollow of the walls and adapted to contain a vaporizing liquid, said tube being in communication with said reservoir.

2. A safe having a body portion, provided with a storage compartment surrounded in part by hollow walls, a reservoir located adjacent the bottom portion of the safe below said compartment and adapted to contain a vaporizing liquid, a tube mounted in the hollow of the walls and adapted to contain a vaporizing liquid, said tube being in communication with said reservoir, and arranged to discharge vapor generated therein into the hollow wall of the safe.

3. A safe structure provided with a storage compartment and a hollow wall upon each side and the back thereof, a relatively shallow tube located in the hollow of each of said walls adjacent the exterior of the same, said tubes being adapted to contain a vaporizing fluid and to communicate with the hollow of the wall within which they are located, and communicating at their lower ends with reservoirs containing a vaporizing liquid.

4. A safe structure comprising a storage compartment, surrounded at least in part by hollow walls, means below said compartment to contain a vaporizing liquid and tubes communicating with said containing means and extending upwardly into the hollow walls of the safe, said tubes being adapted to discharge generated vapor into the hollow of the walls.

5. In a safe structure, a storage compartment, spaced walls at the side of said compartment, an auxiliary reservoir within said walls and adapted to contain a vaporizing liquid to discharge vapor into the space between said walls upon the application of heat, and a main reservoir with which said auxiliary reservoir communicates to supply said auxiliary reservoir with vapor when the applied heat is of long duration.

6. In a fire proof safe, a storage compartment, spaced walls at the side of said com-

partment, an auxiliary reservoir located between said walls and adapted to contain a vaporizing liquid to initially supply vapor to the space between the walls when the safe is subjected to heat, and a main liquid supply to furnish such vapor during a continued application of heat.

7. In a fire proof safe, a storage compartment, spaced walls at the side thereof, means between said walls to contain a relatively small supply of a vaporizing liquid adapted to be quickly vaporized and discharged between said walls upon the application of heat to the safe, a reservoir containing a larger supply of a vaporizing liquid, said means being in communication with said reservoir whereby the liquid in the latter is vaporized and discharged upon a continued application of heat to the safe.

8. In a fire proof safe, a storage compartment, spaced walls at the side of said compartment, a relatively flat tube extending vertically of the safe and positioned against the outer of said walls, said tube being adapted to contain a vaporizing liquid and to discharge generated vapor into the space between the safe walls and the tube being in communication with the reservoir containing a vaporizing liquid.

9. In a fire proof safe, a storage compartment surrounded by spaced walls, said safe being provided with a removable bottom, a reservoir for containing a vaporizing liquid adapted to be placed in the lower part of the safe when the bottom is removed, and a tube the interior of which is in communication with said reservoir, said tube extending upwardly into the space between the walls of the safe and adapted to discharge generated vapor therein.

10. In a safe construction, a storage compartment surrounded upon three sides and at the top by spaced walls, the spaces at the said sides and the top of the safe being in communication with each other, a reservoir containing a vaporizing liquid mounted in the lower part of the safe, and a tube extending from said reservoir upwardly into the space between said walls and adapted to discharge vapor within said space when the safe is subjected to heat.

11. A fire proof safe provided with a storage compartment, a swinging door for closing said compartment and giving access thereto, locking mechanism within said door, a reservoir within the door for containing a vaporizing liquid, and means affording communication between said reservoir and the locking mechanism of the safe, whereby vapor is conducted to the latter when the safe door is subjected to heat.

12. In a fire proof safe, a storage compartment, a door for closing and giving access to said compartment, locking mechanism within the door, a reservoir within the door and

occupying substantially the entire space between the walls thereof, with the exception of that occupied by the locking mechanism, said reservoir containing a vaporizing liquid, and a tube leading from the upper part of said reservoir into the part of the door containing the locking mechanism, to flush said part with vapor when the door is subjected to heat.

10 13. A fireproof safe provided with a storage compartment, a swinging door for closing said compartment and giving access thereto, locking mechanism within said door, a reservoir within the door for containing a vaporizing liquid, and means affording communication between said reservoir and the locking mechanism of the safe, whereby vapor is conducted to the latter when the safe door is subjected to heat, and means normally closing communication between said reservoir and the atmosphere to prevent evaporation of the liquid.

14. In a fireproof safe, a storage compartment, a door for closing and giving access to said compartment, locking mechanism within the door, a reservoir within the door and occupying substantially the entire space between the walls thereof with the exception of that occupied by the locking mechanism, said reservoir containing a vaporizing liquid, and a tube leading from the upper part of said reservoir into the part of the door containing the locking mechanism, to flush said part with vapor when the door is subjected to heat, and means normally closing communication between said reservoir and the atmosphere to prevent evaporation of the liquid.

15. A safe structure provided with a storage compartment and a hollow wall upon each side and the back thereof, a relatively shallow tube located in the hollow of each of said walls adjacent the exterior of the same, said tubes being adapted to contain a vaporizing fluid and to communicate with the hollow of the wall within which they are located, and communicating at their lower ends with reservoirs containing a vaporizing liquid, valves controlling both said communications, said valves normally closing said communications to prevent evaporation of the liquid in the tube and reservoirs.

16. A safe structure comprising a storage compartment, surrounded at least in part by hollow walls, means below said compartment to contain a vaporizing liquid and tubes communicating with said containing means and extending upwardly into the hollow walls of the safe, said tubes being adapted to discharge generated vapor into the hollow of the walls, and means normally closing the communication between said

tubes and said containing means to prevent evaporation of the liquid.

17. A safe structure comprising a storage compartment, surrounded at least in part by hollow walls, means below said compartment to contain a vaporizing liquid and tubes communicating with said containing means and extending upwardly into the hollow walls of the safe, said tubes being adapted to discharge generated vapor into the hollow of the walls, and means to restrict communication between the tube and the containing means when the safe is turned from its normal position to prevent a rapid leakage of the vaporizing liquid.

18. A safe structure provided with a storage compartment and a hollow wall upon each side and the back thereof, a relatively shallow tube located in the hollow of each of said walls adjacent the exterior of the same, said tubes being adapted to contain a vaporizing fluid and to communicate with the hollow of the wall within which they are located, and communicating at their lower ends with reservoirs containing a vaporizing liquid, valves controlling both said communications, said valves normally closing said communications to prevent evaporation of the liquid in the tube and reservoirs.

19. A safe structure provided with a storage compartment and a hollow wall upon each side and the back thereof, a relatively shallow tube located in the hollow of each of said walls adjacent the exterior of the same, said tubes being adapted to contain a vaporizing fluid and to communicate with the hollow of the wall within which they are located, and communicating at their lower ends with reservoirs containing a vaporizing liquid, valves controlling both said communications, said valves normally closing said communications to prevent evaporation of the liquid in the tube and reservoirs, and adapted to restrict said communication when the safe is turned from its normal position to prevent a rapid leakage of the liquid into the hollow of the safe walls.

20. A safe structure comprising inner and outer compartments having spaced walls, a reservoir adapted to contain a vaporizing liquid mounted between said walls and adapted to discharge vapor into the space therebetween, a door for said safe, and vapor outlets adjacent the edge of the door to permit the discharge of vapor between the edges of the door and safe when the door is closed if the safe is subjected to heat.

In witness whereof, I have hereunto set my hand this 26th day of January, 1925.

CHARLES F. KLOSS.
